(57) CLAIM

The ornamental design for a hood for an automobile, as shown and described.

DESCRIPTION

FIG. 1 is a perspective view of a hood for an automobile;

FIG. 2 is a top plan view thereof;

FIG. 3 is a front view thereof; and,

FIG. 4 is a right side view thereof, a left side view being a mirror image thereof.

The broken lines showing on the drawing disclosure are for illustrative purposes only and form no part of the claimed design.
